UNITED STATES PATENT OFFICE

TORRIS H. ALFREDS, OF PARK RIDGE, ILLINOIS, ASSIGNOR TO WILLIAM S. FERRIS, NOW TRADING AS DO/MORE CHAIR COMPANY, OF ELKHART, INDIANA

BACK-REST ARRANGEMENT FOR CHAIRS

Application filed June 13, 1928. Serial No. 284,966.

This invention relates to improvements in back rest arrangement for chairs and it consists of the matters hereinafter described and more particularly pointed out in the appended claims.

The primary object of the invention is to provide a simple arrangement of parts between the back rest post and seat of a chair whereby the back rest may be readily adjusted to the proper position relative to said seat.

The above mentioned object of the invention, as well as others together with the many advantages thereof will more fully occur as I proceed with my specification.

In the drawings:

Fig. 1 is a view in side elevation of a chair embodying my improved back rest arrangement.

Fig. 2 is a horizontal sectional view on an enlarged scale as taken on the line 2—2 of Fig. 1.

Fig. 3 is a vertical sectional view on a further enlarged scale as taken on the line 25 3—3 of Fig. 2.

Fig. 4 is a detail view of a fragment of the seat frame plate showing the manner in which a certain eye bolt is connected thereto.

As illustrated and described herein, the improved construction is embodied in that type of chair which has now become known as a "stenographer's correct posture" chair but as will be apparent, said construction may also be embodied in other types of chairs 35 where the peculiar characteristics make it of advantage to do so.

Referring now in detail to that embodiment of the invention illustrated in the accompanying drawings, the chair which is made substantially all of metal, includes a supporting base or standard 1 comprising a plurality of tubular legs 2—2, the top ends of which are held in closely grouped relation by top, bottom and intermediate spiders

45 3, 4 and 5 respectively. The bottom ends of the legs are bent outwardly to provide that spread necessary for stability and the extremities thereof carry casters or domes 6 upon which the chair may be readily moved about.

In the top end of said base or standard and having suitable rotative bearing as well as vertical adjustment with reference to said spiders is a seat post 7 on the top end of which is fixed a sleeve 8 having a radial flange 8^a at its top and a pair of rearwardly extending spaced ears 8^b, the purpose of which will later appear.

9 indicates as a whole the seat frame of the chair. Said frame which is rectangular in plan, is wider than it is deep and it consists of front and rear members 10 and 11 respectively and side members 12, all of angle bar stock with the vertical flanges facing upwardly from the horizontal flange which

faces inwardly. Connecting the mid portions of said front and rear members of the seat frame is a metallic plate 13 of a width less than that of said seat frame. Said plate includes a horizontally disposed mid portion 14 and front and rear portions 15 and 16 respectively.

Said front and rear portions are inclined upwardly in opposite directions and at slightly different angles and the margins thereof engage against the underside of the

70 horizontal flanges of the seat frame members 10 and 11 and are secured thereto as for instance by spot welding. In the rear portion of the plate, midway between its side edges is provided a depressed portion 17 having an 75 opening 18 therein. The central part of said mid portion 14 of the seat frame plate engages upon and is fixed to the flange 8^a of the sleeve 8. By reason of the different angular

80 inclinations of the plate portions 15 and 16 respectively, the seat frame is pitched or tilted downwardly toward the rear and associated with the seat frame mentioned is a seat cushion or member 19 so fitting within the upright flanges of the seat frame members as to be removable therefrom, when so desired.

20 indicates as a whole a back rest supporting post the bottom end 21 of which is bent in a generous curve so that its extremity may be positioned between the ears 8^b on the sleeve and pivoted thereto by a horizontally disposed pin or bolt 22. In the straight portion of said end 21 of the back rest post 20 is rotatively mounted the sleeve or hub 23 of a

100

hand wheel 24. This sleeve which is internally threaded has opposed shoulders engaging opposite sides of said post portion so that while it may be rotated or turned therein, it cannot be moved endwise therefrom in a manner permitting its withdrawal.

25 indicates a bolt or screw, the top end of which is made in the form of an eye 26. Said bolt passes down through the opening 18 in the depressed portion 17 of the seat plate part 16 and a pin 27 which is seated on said depressed portion, with its ends extending under portions of said plate part at each side of said depression, passes through said eye 25 so that the bolt or screw may swing thereon. With this arrangement, the pin preferably has a driven fit at its ends under said plate portions, so that it cannot be easily displaced therefrom. The screw or bolt 25 has threaded engagement with the sleeve 23 of the handwheel 25 and normally its bottom end extends beyond the handwheel and may have a cross pin 28 which prevents disengagement of said screw from said sleeve and handwheel.

25 The top end of the back rest post is substantially straight and to said end is adjustably secured in any suitable manner a back rest member 29. As said back rest member forms no particular part of the present invention, it need not be described in further detail.

When it is desired to adjust the in or out position of the back rest, with reference to the seat, the handwheel is turned in the proper direction. Thus the sleeve 23 will 35 climb up or down on the screw or bolt 25 which turns on the pin 27, to swing the post about its pivot with the ears 8^b on the sleeve 8. In this manner the back rest is swung forwardly and rearwardly. By reason of the 40 screw threaded engagement between the handwheel sleeve and screw or bolt, the back rest remains in the adjusted position without the necessity of extra locking means.

The number of parts employed are indeed 45 few and may be readily assembled so that the cost of manufacturing the arrangement described is materially reduced and said parts are so correlated as to operate efficiently for the intended purpose.

50 While in describing the invention, I have referred in detail to the form, arrangement and construction of the various parts thereof, I do not wish to be limited thereto except as may be specifically pointed out in the appended claims.

I claim as my invention:—

1. A chair embodying therein, a seat frame including a plate and a seat frame post to which said plate is secured, a back 60 rest post pivoted at one end with respect to said seat frame, a threaded member pivoted to said seat frame plate for a swinging movement about an axis parallel with that of the back rest post, a hand wheel having a sleeve 65 rotatively mounted with respect to said post

and having operative engagement with said threaded member.

2. A chair embodying therein, a seat frame including a plate, a seat frame supporting post, a sleeve connecting said post and plate and having at least one ear on the rear side thereof, a back rest post pivoted at one end to said ear, a threaded member pivoted at one end with respect to the seat frame about an axis parallel with that of the back rest post and a hand wheel turnable with respect to said back rest post and engaged with said threaded member. 75

3. A chair embodying therein, a seat frame including a plate, a seat frame supporting post, a sleeve connecting said post and plate and having at least one ear on the rear side thereof, a back rest post pivoted at one end to said ear, a pin carried by said seat frame plate and arranged parallel with the axis of the back rest post, a threaded member swingable on said pin, and a hand wheel turnable with respect to said post and engaged with said threaded member. 80

4. A chair embodying therein, a seat frame including a plate, a seat frame supporting post, a sleeve connecting said post and plate and having at least one ear at the rear thereof, said plate having a depressed portion therein, a seat post pivoted at one end to said ear, a pin disposed in said depressed portion of said plate, a threaded member having an eye swingable on the pin, and a hand wheel journaled in the back rest post and engaged on said threaded member. 95

5. A chair embodying therein a seat, a supporting member therefor, means providing a back rest support, a pivotal connection between said supporting member and said means, a shaft arranged in said supporting member parallel with said pivotal connection, a screw threaded member operatively connected to said shaft so as to swing about the axis thereof, and a member secured in a part of said back rest support providing means and having an opening therein in which said screw threaded member has a screw threaded engagement for causing movement of said back rest support providing means about said pivotal connection. 105

6. A chair embodying therein a seat, a supporting member therefor, means providing a back rest support, a pivotal connection between said supporting member and said means, a shaft arranged in said supporting member parallel with said pivotal connection, a screw threaded member operatively connected to said shaft so as to swing about the axis thereof, and a member secured in a part of said back rest support providing means in a manner permitting a turning movement therein and with which said screw threaded member has a threaded engagement. 115

7. A chair embodying therein a seat, a 120

supporting member therefor including a pair of laterally spaced, rearwardly extending portions, means providing a back rest support, a portion of which is disposed between and has a pivotal connection with said laterally spaced, rearwardly extending portions of said supporting member, a shaft arranged in said supporting member parallel with said pivotal connection, a screw 5 threaded member operatively connected to said shaft so as to swing about the axis thereof and an element secured in said back rest support providing means and having a screw threaded opening therein in which said 10 screw threaded member is engaged for causing movement of said back rest support providing means about said pivotal connection.

15

In testimony whereof, I have hereunto set
20 my hand, this 9th day of June, 1928.

TORRIS H. ALFREDS.
